UNITED STATES PATENT OFFICE.

JOHN T. HAY, OF UNION CITY, INDIANA.

AUTOMATIC JOURNAL-BOX TAKE-UP.

1,108,366.

Specification of Letters Patent.

Patented Aug. 25, 1914.

Application filed April 11, 1913. Serial No. 760,481.

To all whom it may concern:

Be it known that I, JOHN T. HAY, a citizen of the United States, residing at Union City, in the county of Randolph and State of Indiana, have invented certain new and useful Improvements in Automatic Journal-Box Take-Ups, of which the following is a specification.

The object of this invention is to provide automatic means for moving bearing brasses toward the shaft or pin mounted in them to take up wear, and the object is to adjust the two principal diametrically opposite brasses independently of each other and proportionately to the wear on each so as to retain the axis of the pin at its original position, this invention being an improvement on the mechanism shown and described in my Patent No. 1,058,862 for automatic take-up for journal boxes, issued April 15, 1913.

I accomplish the above and other objects which will hereinafter appear, by the mechanism illustrated in the accompanying drawings, in which—

Figure 1 is a view in side elevation, and partial vertical section of one end of the connecting rod with my improvements shown in operative position adjusting bearing brasses to a crank pin. Fig. 2 is a view on a larger scale in section on the line 2—2 of Fig. 1, and Fig. 3 is a section on the line 3—3 of Fig. 1. Fig. 4 is a view in side elevation and partial section of a modified form of my device as applied to the connecting rod of an internal combustion engine.

Like characters of reference indicate like parts throughout the several views of the drawings.

I have only shown one end of a connecting rod in Fig. 1, inasmuch as the other end is a duplication of the part here shown, and it will be understood that such is the case and that the illustration and description here given are to apply equally to both ends of the rod. The body of the rod is here shown as comprising two parallel bars 5 which are retained a fixed distance apart by suitable cross bars 6 of any required number. Supported by the bars 5 is a stirrup comprising the stem-members 7 contacting with the outer sides of the bars 5 and connected at their outer ends, beyond the ends of the bars 5 by a transverse member having an extension 8 taking between the two bars 5. The inner ends of the stems 7 are connected and spaced apart by suitable plates 9. 10 is a

crank pin, and the pin 10 is mounted between two bearing brasses 11 and 12. These brasses 11 and 12 have a close sliding fit between the two bars 5 and their dimensions between said bars 5 equal the diameter of the pin 10, as shown by the dotted lines in Fig. 1, whereby the wearing away of the brasses by contact with the pin 10 will remove all of the material of said brasses adjacent the pin leaving no material of one brass to contact with that of the other above and below the pin as would occur were these brasses greater than the diameter of the pin in the directions stated. The extension 8 of the transverse stirrup bar presses and holds the brass 12 against the pin 10, and block 13 mounted between the bars 5 presses and holds the brass 11 in contact with said pin 10.

I will now describe the mechanism by which the extension 8 and block 13 are automatically moved toward the pin 10 to take up any wear of said boxes. Pivoted at their lower ends to the lower bar 5, are the levers 14 and 15 which are located on opposite sides of the pin 10, and each lever has a bearing extension 16 on the side next to the pin 10 which bears against said pin and is held in constant contact therewith by the action of a spring 16' on a rod 17. This rod 17 passes through the upper end of the lever 15 and is pivoted to the lever 14. The outer end of rod 17 is screw-threaded and receives a nut 18 which limits the distance apart of the upper ends of the levers 14 and 15, and a given position of the nut 18 is held by the jam-nut 19. On the opposite side of the lever 15 is a loosely sliding nut 20, and the end of the lever 15 is preferably spherical, as shown, to provide a better acting bearing for the nuts 18 and 20. Farther out on the rod 17 is the nut 21 and its lock nut 22 and between nuts 20 and 21 is the spirally wound spring 16', the tension of which is regulated by the adjustment of the nuts 21 and 22 on the rod 17. The action of the spring 16' holds the bearing extensions against the pin 10 with a regulated pressure under normal conditions, but when the pin 10 expands by becoming overheated the separation of the upper ends of the levers 14 and 15 is permitted by the compression of the spring.

The block 13 is provided with a screw-threaded bore to receive the correspondingly threaded end of a short shaft 24, the other end of which shaft is journaled in a

block 25 and fastened to the two bars 5. The plates 9 support a block extension between them having a screw-threaded bore into which the threaded end of a shaft 26 is 5 screwed, and the other end of this shaft is journaled in the block 25. Splined or otherwise secured upon the shafts 24 and 26 are the gear wheels 27, the teeth of which engage the threads of worms 28 (see Fig. 2 10 and shown in dotted lines in Fig. 1) mounted on suitable transverse shafts above said gear wheels. Mounted on one end of each of these shafts is a circular disk 29 having an annular flange 30. A pair of friction 15 pawls 31 and 32 for each disk 29, act in conjunction with their flanges 30. The upper ends of the pawls 31 are pivoted to a connecting rod 33 by which they are connected with the upper end of the lever 14 and the 20 lower ends of the pawls 32 are pivoted to the lower bar 5. The inner ends of each pair of pawls 31 and 32 are separated from each other by means of springs 34. The pawls 31 are in oppositely oblique relation 25 to each other and the same is true of the pawls 32. An oscillatory movement transmitted to the pawls 31 by a reciprocating movement of the connecting rod 33 will cause said pawls to clamp against the 30 flanges 30 of their respective disks and move the disks in the directions shown by the arrows. Back movement of the disks is prevented by the pawls 32. This construction above described is for the same purpose as 35 the ordinary notched wheel and ratchet construction and is preferable because the pawls will take frictional hold of the flanges 30 at any point of the latter thereby permitting of a closer adjustment than would 40 be possible by the use of a toothed ratchet wheel in which the adjustments would be limited to the size of the teeth.

In the construction shown in Fig. 1, the pin 10 is provided with annular flanges 36, 45 preferably with oblique inner faces to contact with the bore of brasses 11 and 12 to prevent the escape of lubricating oil from the journal. The bars 5 are provided with inwardly extending flanges 37 which prevent lateral displacement of the bearing brasses 11 and 12 and block 13.

Undue looseness of the levers 14 and 15 is prevented by a friction plate 38 which is 50 pressed by a spring 39 against the lever 14 and the lever is thereby pressed against the bar 5. The tension of the spring 39 is regulated by a set-screw 40 which passes through a hole in the plate 38 and a transverse slot in lever 14 and is seated in a threaded hole 60 in the bar 5.

In the operation of my device, any looseness due to wear of either of the brasses 11 or 12, will produce an oscillatory movement of the levers 14 and 15 which will continue 65 until the brasses have been moved in far

enough to take up such looseness. The oscillatory movement of lever 14 acting through the connecting rod 33 and pawls 31 will rotate the disks 29 in the directions of their respective arrows and this movement 70 of the disks transmitted through their worm gear connections with the threaded shafts 25 and 26 will move the block 13 toward brass 11 pressing the latter against pin 10, and will move the threaded block extension 75 of plate 9 in an opposite direction thereby drawing the stems 7 of the attached yoke along with it and causing the extension 8 of the cross bar between stems 7 to move toward the pin 10 against the brass 12 forcing the 80 latter into contact with the pin 10.

In the modification shown in Fig. 4, which is for a connecting rod or pitman connected directly to the piston (not shown) by a pin 41 at one end of the rod and with 85 a crank pin 42 at the other end of the rod, it is not essential that the axes of the two pins 41 and 42 be maintained the same distance apart, because there is ample room in 90 the cylinder of an internal combustion engine for the stroke of the piston should the distance between the axes of said pins be somewhat increased. Therefore, I am able to adjust both of the inner brasses toward 95 their respective pins which will be sufficient to keep all of the brasses tight and by connecting this take-up mechanism with a pair 100 of levers similar to levers 14 and 15, bearing against the crank pin 42 I am able to automatically tighten the brasses for both pins 105 41 and 42 as the wear on either set of brasses occurs.

The inner bearing brasses 11' are contacted by the blocks 13' slidingly mounted in the pitman frame. Both of these blocks have 110 bores to receive the ends of a shaft 44. These ends of the shaft 44 are screw-threaded, the thread on that end which is toward the piston pin 41 being preferably of a finer thread and reversing direction from the thread on 115 the end of the shaft on the crank pin 42, whereby, when the shaft 44 is rotated in a direction to move the block 13' nearest the crank pin 42 in the direction of said crank pin, the other block 13' will be moved toward the piston pin 41, but more slowly, which is desirable on account of there not 120 being as much wear on the brass members of the pin 41 as there is on the brass members of the crank pin 42.

Mounted on the shaft 44 is a gear wheel 45 which meshes with a worm 46 on the same shaft on which disk 47 is mounted. The disk has a peripheral flange which is frictionally engaged by the pawls 31' and 125 32', and the pawl 31' is connected by a link bar with the upper end of the lever 14'. This lever 14' and its companion lever 15' have extensions contacting with the pin 42 in the same manner as has previously been 130

described for the construction shown in Fig. 1, and the two levers 14' and 15' are connected together at their upper ends in the manner as described for levers 14 and 15, and it is therefore believed that a repetition of the construction and operation of these parts is unnecessary.

While I have described my invention with more or less minuteness as regards details of construction and arrangement and as being embodied in certain precise forms, I do not desire to be limited thereto unduly or any more than is pointed out in the claims. On the contrary, I contemplate all proper changes in form, construction and arrangement, the omission of immaterial elements, and the substitution of equivalents, as circumstances may suggest or necessity render expedient.

20 I claim:

1. In a journal for rotary shafts, a pair of bearing-brasses disposed on opposite sides of the shaft, screw-operated means to move the bearing-brasses toward the shaft, and means comprising a lever bearing against the shaft for actuating said screw-operated means.

2. In a journal for pitmen shafts, two pairs of bearing-brasses one for each pitman shaft disposed on opposite sides of said shaft, means for mutually adjusting the two sets of brasses, and means comprising a lever contacting the shaft to automatically adjust the bearing-brasses to maintain the original axial relation of the two shafts.

3. In a journal for pitmen shafts, two pairs of bearing-brasses one for each pitman shaft disposed on opposite sides of said shaft, blocks contacting with the brasses, screw-operated means for mutually adjusting the blocks, and means contacting the shaft for operating said screw-means.

4. In a journal for rotary shafts, a pair of bearing brasses disposed on opposite sides of the shaft, screw-operated means to move the bearing-brasses toward the shaft, a pair of levers disposed on opposite sides of the shaft and having extensions bearing against the shaft, and means operated by said levers for actuating said screw-operated means.

5. In a journal for rotary shafts, a pair of bearing-brasses disposed on opposite sides

of the shaft, blocks contacting with the brasses, screw-operated means for moving the blocks in a direction to press the bearing-brasses toward the shaft, a pair of levers disposed on opposite sides of the shaft and having extensions bearing against the shaft, and means operated by said lever for actuating said screw-operated means.

6. In a journal for rotary shafts, a pair of bearing brasses disposed on opposite sides of the shaft, blocks contacting with the brasses, screw-operated means for moving the blocks in a direction to press the bearing brasses toward the shaft, a pair of levers disposed on opposite sides of the shaft and having extensions bearing against the shaft, and pawl and ratchet means operated by said levers for actuating said screw-operated means.

7. In a journal for rotary shafts, a pair of bearing brasses disposed on opposite sides of the shaft, blocks contacting with the bearing-brasses, screw operated means for moving the blocks in a direction to press the bearing brasses toward the shaft, a pair of levers disposed on opposite sides of the shaft and having extensions bearing against the shaft, elastic means connecting the free ends of the levers, gears for rotating said screw means, and pawl and ratchet means operated by said levers for actuating said gear means.

8. In a journal for rotary shafts, a pair of bearing brasses disposed on opposite sides of the shaft and of the same longitudinal dimensions as the diameter of the shaft whereby each bearing brass will have two ends tangent to the shaft, gear operated screw means for independently moving each of the bearing brasses toward the shaft, a pair of levers disposed on opposite sides of the shaft and having extensions contacting with the shaft, and means connecting the levers with the gear means of said bearing brass adjusting screw means.

In witness whereof, I, have hereunto set my hand and seal at Union City, Indiana, this 3d day of April, A. D. one thousand nine hundred and thirteen.

JOHN T. HAY. [L. s.]
